UNITED STATES PATENT OFFICE.

NILS MALMAR, OF BROOKLYN, NEW YORK.

COAT.

SPECIFICATION forming part of Letters Patent No. 239,814, dated April 5, 1881.

Application filed September 11, 1880. (No model.)

To all whom it may concern:

Be it known that I, NILS MALMAR, of Brooklyn, in the county of Kings and State of New York, have invented a new and useful Improvement in Coats, of which the following is a specification.

My invention relates to overcoats provided or supplied with detachable and interchangeable inner linings adapted for different seasons, so that by simply attaching a warmer lining a fall overcoat may be worn even in winter, said lining being described and claimed in Patent No. 214,431, granted to me April 15, 1879.

15 The object of my present invention is to provide an improvement on the invention just referred to, whereby linings of warming capacity corresponding to that of the body-lining may be applied to the coat-sleeves simultaneously with the application of the said body-lining, provisions being made for rapidly and securely attaching the same, and for facilitating the taking off or putting on of the coat with as much ease and comfort to the wearer as if the said linings were permanently sewed in the sleeves in the usual manner.

In the accompanying drawings, Figure 1 represents a general inside view of a coat with the said supplementary lining attached. Fig. 20 2 is a similar view of the same, in which the sleeve is completely turned to expose the sleeve-lining and the body-lining is partly unbuttoned and turned up. Fig. 3 is a sectional detail view of a portion of the sleeve-lining.

35 Similar letters of reference indicate like parts.

A designates the coat, and B the supplementary body-lining, detachably attached along the lapel of the coat by temporary fastening devices a', and at the back by buttons and button-holes, as shown at b.

To accomplish the object of my present in-

vention, I provide for each of the coat-sleeves a supplementary lining, C, and stitch the same to the body-lining B at the shoulder, so that the said sleeve-lining will form one piece with the body-lining, and may be applied and removed simultaneously with the latter. The supplementary sleeve-lining C is buttoned or otherwise temporarily secured to the coat around 45 the armhole, as shown at d, and around the sleeve-cuff, as shown at d'.

The sleeve-lining may, of course, be made independent of the body-lining, and separately attached; but I prefer to stitch them together 55 to form one complete supplementary lining, as before stated, whether used in a skeleton-coat or in a coat having the usual permanent lining.

In order to present the elegant appearance required in a good coat-sleeve, and the smooth 60 surface needed to prevent unnecessary adhesion between the inner coat and the sleeve of the overcoat, so as to facilitate the putting on and taking off of the latter, I provide the supplementary sleeve-lining C with a permanent 65 silk, satin, or other smooth facing, D, stitched to it at cuff and armhole, as shown in Fig. 3.

Having thus described my invention, what I claim as new, and desire to secure by Letters Patent, is—

1. A supplementary lining-sleeve, C, adapted to be attached, as a temporary inner sleeve-lining, to a coat, substantially as set forth.
2. A supplementary lining, B C, consisting of the combination of the sleeve-lining C and body-lining B, made in one piece, by being permanently secured together at the shoulder, and adapted to be attached, as a complete temporary inner lining, to a coat, substantially as specified.

NILS MALMAR.
